UNITED STATES PATENT OFFICE.

JOSEPH SKOWYRA, OF PALMER, MASSACHUSETTS, ASSIGNOR OF ONE-HALF TO JOSEPH SLOMIAK, OF WARE, MASSACHUSETTS.

AUTOMATIC STOP FOR SPINNING MACHINES AND THE LIKE.

Application filed September 4, 1924. Serial No. 735,945.

To all whom it may concern:

Be it known that I, JOSEPH SKOWYRA, a citizen of the Republic of Poland, residing at Palmer, in the county of Hampden and State of Massachusetts, have invented new and useful Improvements in Automatic Stops for Spinning Machines and the like, of which the following is a specification.

This invention relates to improvements in automatic stops for spinning machines and the like and has as its special object the provision of means whereby should a strand of the yarn or thread break, while being operated upon, the driving mechanism for that particular strand will be disengaged preventing entanglement and loss of material.

This and other like objects are attained by the novel construction and combination of parts, hereinafter described and shown in the accompanying drawings, forming a material part of this disclosure, and in which:

Fig. 1 is a fragmentary top plan view showing a portion of a spinning machine made in accordance with the invention;

Fig. 2 is an enlarged top plan view of the same;

Fig. 3 is a transverse sectional view taken on line 3—3 of Fig. 1;

Fig. 4 is a similar transverse sectional view taken on line 4—4 of Fig. 1; and

Fig. 5 is another transverse sectional view taken in a different plane on line 5—5 of Fig. 3.

Throughout the several drawings, the supporting frame is indicated by the numeral 10, here shown to consist of a substantially level and flat plate having along one of its side edges brackets 11, which are used for supporting the drive shaft 12, having on it a pulley 14, over which is trained a belt 15, from some source of power.

On one end of the shaft 12 is a bevel gear 18, meshing with a similar gear 19, secured upon a longitudinally disposed shaft 20, carried in a plurality of brackets 21, rigidly secured upon the plate 10 along one of its longer edges at right angle to the shaft 12.

Also carried in these brackets, above and to the front of the shaft 20, is another shaft 22 on which are loosely journalled rollers 23, the periphery of which are in contact with other rollers 24, freely rotatable upon the shaft 20.

At one end of the rollers 24, are formed clutch elements 25 and engageable therewith

are other clutch elements 26, formed on the sliding sleeves 27, slideable on the shaft 20, and rotated thereby by means of the keys 28. The sleeves 27 have annular recesses 29 engaged by forks 30, formed at the ends of levers having raised parts 32, vertical stems 33, and lower horizontal parts 34, parallel with the upper portion 32, the lower elements 34 being pivoted on screws 35 fixed to the plate 10.

These clutch elements are normally drawn into operative engagement by the pull of tension springs 36, one end of which is secured to the plate 10, and the other to the levers in a manner clearly apparent from Fig. 2. The clutch elements are held from engagement by means later to be described.

Fixed upon the shaft 12 is an eccentric hub 38, to which is fitted a strap or band 39, held thereon by flanges and a screw 40. To the opposite or front side of the eccentric band is secured a boss 41 from which projects a connecting rod 42 pivotally engaged at its outer end with a reciprocating bar 44, the said bar extending longitudinally of the apparatus parallel with the shaft 20 and is guided for a reciprocating movement in a plurality of brackets 45 fixed to the table 10.

Fixed upon the side of the bar 44, adjacent to the rollers 24 and spaced in accordance therewith, are projections 46 carrying pivoted arms 47 having hook like extremities 48 adapted to overlie and to rest over the thread or yarn 50 being drawn through the rollers 23 and 24, so as to guide the same 90 and cause it to be distributed uniformly between the said rollers 23 and 24.

Also formed with the arms 48 are downturned projections 51 adapted to engage, when the arms are allowed to fall by a loose 95 yarn, with extensions 53, formed with the vertical arms 33 of the lever 34 so as to press the same toward the shaft 12 which motion obviously disconnects the clutches and causes cessation of rotation of the pair of rollers 100 20 and 22 corresponding with the particular arms 47 which may be in contact.

The bar 44 is reciprocated back and forth by a rotation of the driving shaft 12 and eccentric 38 and the arms 47 are normally 105 held in the position shown in Fig. 5 by the unbroken yarn 50, in which position of the arms the projections 51 thereof will not engage the extension 53 of the lever 34. Should the yarn 50 break or become suffi- 110

ciently loose, the arm 47 will drop so that the projection 51 will engage the extension and move the lever 34 to disengage the clutch as aforesaid.

5 In order to hold the clutches disengaged, spring detents 55 secured to the plate 10 contact with the levers 34, so as to hold the clutches in a disengaged position until the operator shall have mended the broken 10 strand of yarn, which permitted the arm 47 to drop, raise the detent and manually press the clutches again into engagement.

From the foregoing it will be readily understood that any desired number of the 15 rollers between which the threads are drawn are controlled in their operation by a single reciprocating bar 44 so that should any individual strand become broken the particular set of rollers will become disengaged from 20 further operation and until the mechanism has been reset by the operator and without it affecting the remaining strands, thereby preventing a waste of yarn in an obvious manner.

25 Having thus described my invention, what I claim as new and desire to secure by Letters Patent; is—

1. In a spinning machine, the combination 30 with a driven shaft disposed at the end of the machine, a second shaft disposed at a right angle thereto, a plurality of rollers loosely mounted thereon, other rollers mounted thereabove the peripheries of each pair being in intimate contact, clutch ele-

ments formed with the lowermost of said 35 rollers, sleeves keyed to said shaft and moved longitudinally thereof, clutch elements formed with said sleeves engageable with the clutch elements of said rollers, means for normally holding said clutch elements in engagement, a bar moved reciprocatively by said driving shaft, said bar being parallel to the axis of the second named shaft, thread carriers engaged with said bar, and means combined with said thread 40 carriers adapted to disengage said clutches upon the breaking of the thread leading to the rollers with which they are engaged.

2. In a spinning machine, the combination 45 with a horizontal shaft, one or more thread carrying rollers rotatable thereon, clutch elements formed at one end of said rollers, other clutch elements slidably keyed to said shaft, levers operatively engaged with said 50 keyed clutch elements, means for normally holding said levers in position to maintain said clutch elements in engagement, a bar mounted slidably parallel to said shaft, means for actuating said bar reciprocatively, thread carriers engaged with said bar, 55 one for each of said rollers, and means operative coincident upon the breaking of a thread adapted to make contact with said levers, whereby said clutch elements are disengaged.

In testimony whereof I have affixed my signature.

JOSEPH SKOWYRA.
